UNITED STATES PATENT OFFICE.

EMERY B. COLSON AND HOSEA CLINTON GREEN, OF HUTCHINSON, KANSAS.

TOBACCO CAN.

Application filed November 21, 1923. Serial No. 676,107.

To all whom it may concern:

Be it known that we, EMERY B. COLSON and HOSEA CLINTON GREEN, citizens of the United States, residing at Hutchinson, in the county of Reno and State of Kansas, have invented certain new and useful Improvements in Tobacco Cans, of which the following is a specification.

This invention relates to certain new and useful improvements in tobacco cans and has particular reference to cans of this kind, wherein provision is made for maintaining the tobacco or contents thereof moist and fresh.

15 The primary object of the invention is to provide a tobacco can having a cover provided with novel and efficient means of a simple nature for maintaining the tobacco within the can in a fresh and moist condition.

20 Another object of the invention is to provide means for readily replenishing the supply of moisture without requiring removal of the cover from the can.

25 Still another object of the invention is to provide a tobacco can covering having an absorbent sheet arranged within the top thereof and associated with means which may be readily manipulated from time to time for supplying additional moisture to said absorbent sheet.

30 Other objects will become apparent as the nature of the invention is better understood, and the same consists in the novel form, combination, and arrangement of parts hereinafter more fully described, shown in the accompanying drawing, and claimed.

35 In the drawing, wherein like reference characters indicate corresponding parts throughout the several views:

Figure 1 is a top plan view of a tobacco can constructed in accordance with the present invention.

40 Figure 2 is a fragmentary substantially central vertical sectional view of the device shown in Figure 1.

Figure 3 is a fragmentary sectional view of the can cover, as the same appears prior to engagement of the prongs thereof with the absorbent sheet, and

45 Figure 4 is a view similar to Figure 3 as the cover appears after engagement of the prongs with the absorbent sheet.

50 Referring more in detail to the drawing, 5 indicates the usual open top body of a

tobacco can that may be of any desired or preferred form, and that is preferably constructed of sheet metal and formed with an endless bead 6 near the upper edge thereof to form a stop engaged by the flange 7 of the closure cap or lid 8 that is slipped onto the top of the body 5, as shown in Figure 2.

55 In accordance with the present invention, the cap 8 is constructed of sheet metal and has a plurality of spaced spurs 9 struck downwardly or inwardly therefrom at points adjacent the margin of the same as shown clearly in Figure 1. An absorbent

sheet or blotter 10 is arranged within the cap or cover 8 in contact with the under or inner surface of the top wall of said cap and cover and substantially completely covering said surface, the prongs 9 being projected through the absorbent sheet 10

and clinched onto the under side of the absorbent sheet as shown clearly in Figures 2 and 4 for retaining said sheet in position. In this manner, the absorbent sheet covers

50 the openings left by punching the prongs 9 from the top wall of the closure or cap. The top wall of the cover or cap is provided with a central flared neck 11 within which is positioned a sponge 12, which, in practice, is adapted to be soaked with water and placed upon the portion of the absorbent sheet within the lower portion of the neck 11 as shown in Figure 2, whereby the moisture from said sponge will be transmitted to the absorbent sheet 10 for maintaining the contents of the can body in a fresh and moist condition. The upper end of the neck 11 is closed by means of a cork

55 or stopper 13, also of tapered form, and which may be readily removed for permitting removal of the sponge 12 whenever it is desired to replenish the moisture in said sponge. Thus, the supply of moisture to the sheet 10 may be replenished with

60 out necessitating removal of the cover or cap 8 of the can. In the initial use of the device, the stopper 13 is merely placed in the neck 11 sufficiently tight to permit its ready accidental displacement from the neck, and the moisture may be subsequently squeezed from the sponge to be

65 taken up by the absorbent sheet 10, by further forcing the stopper 13 into the neck 11.

70 While we have shown and described, the cover 8 as being of the removable slip on

type, it is obvious that the same may be of the hinged type or sliding type without departing from the spirit and scope of the invention as claimed.

5. What we claim as new is:

In a tobacco can, a cover having an absorbent sheet secured against and covering substantially the entire under surface thereof, said cover having a top wall provided with a neck through which a portion of the absorbent sheet is exposed, a compressible moisture retaining element within the neck upon the exposed portion of the

absorbent sheet, a removable closure for the neck positioned above said moisture retaining element, the means for securing the absorbent sheet against the under surface of the cover comprising a plurality of marginal downwardly directed tongues struck from the top of the cover and projecting through and clinched against the under surface of the absorbent sheet.

In testimony whereof we affix our signatures.

EMERY B. COLSON.
H. CLINTON GREEN.
